UNITED STATES PATENT OFFICE

JOSEPH A. MARTOCELLO, OF PHILADELPHIA, PENNSYLVANIA

SYSTEM FOR AERATING ICE CANS

Application filed February 15, 1927. Serial No. 168,267.

My invention relates to aerating connections for ice cans and to so-called can baskets comprising units of a number of cans each of which is used in the manufacture of ice.

5 One purpose of my invention is to provide bottom insertion of air within each can and to connect up the opening removably with an outside lateral carried by the basket.

A further purpose is to provide a lateral 10 and aerating pipe connections therefrom with an intermediate valve having a removable valve member containing an air restriction and capable of being substituted by another valve to give a different air restriction.

15 A further purpose is to provide a trap for dirt or other foreign material in the air line of an ice can air supply and in the form of a removable restricted valve opening.

A further purpose is to provide a novel 20 bottom air inlet.

A further purpose is to provide an ice can basket with a lateral extending along the ends of the cans and with connections extending down the ends of the cans and along 25 the bottoms thereof to a bottom air inlet.

Further purposes will appear in the specification and in the claims.

I prefer to show one form only of my invention with slight modifications, selecting 30 a form which is practical, efficient, reliable and inexpensive and which at the same time well illustrates the principles of my invention.

Figure 1 is a perspective of the can, basket 35 and associated parts.

Figure 2 is a fragmentary, vertical section corresponding to line 2—2 of Figure 1 but with a can of slightly different shape.

Figure 3 is a fragmentary section through 40 the bottom of the can at an air inlet.

Figure 4 is a side elevation and vertical longitudinal section at and through the joint between the lateral and the header.

Figure 5 is a section showing a slight modification as compared with Figure 2.

Figure 6 is a fragmentary enlarged section of a portion of Figure 5. It corresponds with line 6—6 of Figure 7.

Figure 7 is a side elevation partly in section upon the line 7—7 of Figure 6.

Figure 8 is a fragmentary vertical section showing a further modification.

Figure 9 is a fragmentary perspective partly broken away to show the interior, of 55 an additional form of my invention.

In the drawings similar numerals indicate like parts.

In the can basket 15 shown the cans 16 have the usual upper rims 17 forming outwardly extending end ledges which are supported from side frame members 18 and 19 by strips 20 secured to the side frame members.

The side frame members are united by end 60 frame members 21 secured to the side frame members by any suitable means such as bolts 22. Stiffening transverse members 23 and 24, 25 and 26 are shown united to the side frame members at 27. They perform the further function of supporting lifting pins 65 28 to be engaged by the usual crane lifting hooks through which the baskets are handled. Upward movement of the cans within the basket is prevented by removable plates 70 29.

Under the side of one of the frame members is secured a lateral 30 which may extend about the end of the basket also as at 30' for more convenient placing of a fitting 31. The upper end of fitting 31 supports a fixed valve 80 plug 32.

Hose connections 33, 33' from a header 34 terminate in nozzles 35 fitting into openings 36 in the valve plugs. The openings are suited to receive thawing needles and are surrounded by guides 37 for these needles. The nozzles open spring-pressed valve closures 38 within the plugs. The spring-pressed valves are held to their duty by hollow plugs 39.

Each air inlet shown takes place through 85 the bottom of the can which is apertured at 40 so as to receive tubular boss 41. The boss extends above the bottom of the can and serves as a discharge nozzle. The boss is carried by plate 42 which directly or through a gasket 90 seals against the bottom of the can and is united with the can as by rivets 43.

The air inlet opening 44 is in line with and connects with a socket opening 45 for pipe terminal 46. The pipe terminal is held and is 100

sealed by a stuffing box gland 47 and packing 48.

From the lateral 30 to the terminal pipe 46 I show three different but much similar connections. One extends downwardly at 50 along a groove 51 in the end of the can (Figures 1 and 2) passing through the end of the can below the level of the bottom of the can. In another form the pipe extends diagonally 10 as at 50' (Figure 5) between the cans and passes through the lower side edge of the can below the level of the bottom of the can as at 51'.

In a third form shown in Figure 8 the lateral is placed inside the side frame member 18 and the pipe 50² extends downwardly between a top can rim and the can into and down along the groove 51 in the side of the can following the groove at the bottom and passing 20 through the bottom edge of the can as in the construction shown in Figure 2.

The connection with the lateral in either form is effectively the same, differing in the two merely in the relative partial rotation of 25 the lateral within its strap 52 from its position in Figure 2 to its position in Figure 5. In each the connection is radial to the pipe.

The pipe 50, 50' or 50² terminates at its upper end within a socket 53 in a fitting 54. The 30 pipe is held and sealed by gland 55 and packing 56. The fitting 54 carries a valve body having a valve opening 57, an intermediate relatively enlarged tubular opening 58, and a restricted terminal 59 within the threaded 35 end 60 which is screwed into the lateral.

Within the opening 57 is placed a tapered valve member 61 adapted to be turned by handle 62 to shut off the air passage through the pipe 50 or 50', or to allow the air to pass 40 into this pipe according to the position of the handle 62.

The passage through the valve plug is restricted at 63 and is desirably smaller than opening 59. Whatever the connection with 45 the lateral and whether used in can basket air supply with drop tube constructions or in other air supply the use of such a valve element permits substitution of other valve plugs to give different restrictions as desired 50 and utilizes the space between the restricted valve opening and the lateral as a trap for dirt, scale and other foreign matter which may have passed through the opening 59. After 55 the cake is frozen the plug may be removed and the dirt and scale may be blown out.

When the can basket is not in place the nozzle 35 is sealed in a blind socket 64 conveniently located. When the can basket has been placed in position the nozzle is removed from 60 this blind socket and is connected with the plug opening 36 so that air is available for all of the cans of the basket.

In Figure 9 the lateral is interrupted at intervals to receive a hollow union 65 which is 65 cast integral with a bracket 66 by which the

lateral may be supported against the side frame member or bar 18. The parts of the lateral are threaded into the union and the valve construction and seal and support for tube 50' are carried by the union. A passage 67 of relatively enlarged section as compared with 70 restricted opening 59 communicates with the interior of the union, corresponds generally with the tubular opening 58 communicating with the valve space in which plug 61 fits.

The valve plug 61 carries a restricted opening 63 and the lower part of the fitting is threaded externally. It is internally recessed 75 to receive the tube 50' and to provide for cap 55 and packing 66 clamped between the bracket on the one side and the end of the threaded portion of the fitting on the other.

Air from the lateral will pass from it to all of the pipes 50 or 50' which may be connected with it and in which the reducing 80 valve plugs are turned so as to open the passages. This will ordinarily include the entire list of pipes 50 or 50' or 50² through which the air will pass, entering the bottoms of the cans until the condition of the ice in the cans warrants cutting them off one by one from the air connection by their individual valves or disconnecting the air supply pipe 33 so that the can may be lifted by a suitable crane to the position in which the ice is to be removed from its cans.

It will be evident that the reducing valve plug trap will perform its double function not only in the locations indicated but also in any air passage by which aeration is secured.

In view of my invention and disclosure variations and modifications to meet individual whim or particular need will doubtless become evident to others skilled in the art, to obtain part or all of the benefits of my invention without copying the structure shown, and I, therefore claim all such in so far as they fall within the reasonable spirit and scope of my invention.

Having thus described my invention, what I claim as new and desire to secure by Letters Patent is:—

1. In an ice can basket, a basket frame, a lateral adapted at intervals for air withdrawal to the cans, a fitting at each point of withdrawal, a valve body integral with the fitting and having a restricted opening into the interior of the fitting and enlarged between the opening and the interior, a tapered valve plug in the valve body having a restricted opening and an air pipe connected with the valve body.

2. In an ice can basket, a basket frame, cans supported therein, a lateral along the frame adapted for free air withdrawal at intervals, a fitting in each interval having a restricted opening from the fitting and enlarged between the opening and the interior, a valve carried by the fitting and a trap in the valve.

3. In ice making machinery, an air lateral, a fitting therein having a constricted inlet opening, a valve passage and a valve plug in the passage having an opening smaller than the opening in the fitting within the lateral, adapted to close the air supply or to pass air therethrough while trapping foreign matter from the air.

4. In ice making machinery, an air lateral, an air fitting therein having a valve passage and a valve plug therein held in wholly by friction and having an opening smaller than the opening in the fitting within the lateral, adapted to close the air supply or to pass air therethrough while trapping foreign matter from the air and removable to remove the foreign matter trapped.

5. In ice aerating apparatus an air lateral, a fitting adapted for screw connection with the air lateral and having a restricted opening which then lies within the lateral, a transverse valve plug in an opening in the fitting and having a passage, an air restriction in the valve smaller than the passage, a pipe socket communicating with the opening in open position of the valve and a threaded gland adapted to tighten the packing against a pipe within the socket.

6. In ice aerating apparatus, a valve fitting adapted to screw into an air lateral and having an inlet opening which then lies within the lateral and a larger section forming a pocket adjacent to the opening, a removable plug for said valve adapted to restrict the air passage through the valve according to the size of restriction in the plug selected and in one position transversely closing the pocket, a pipe socket in close communication with the valve and means for holding the pipe in the socket.
